UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

COVER-LOCK.

1,398,499.

Specification of Letters Patent.

Patented Nov. 29, 1921.

Application filed March 31, 1919. Serial No. 286,352.

To all whom it may concern:

Be it known that I, GEORGE A. BURNHAM, a citizen of the United States, and resident of Saugus, in the county of Essex and State 5 of Massachusetts, have invented an Improvement in Cover-Locks, of which the following is a specification.

This invention relates to a lock for securing the removable cover to the body of a receptacle and is an improvement on the lock 10 shown in application Serial No. 210,394, filed January 4, 1918.

The object of this invention is to provide a device for the purpose described which is 15 easy to operate, cheap in construction and which securely holds or locks the cover in position on the body of the receptacle against any jarring of the receptacle.

The means by which I attain the object 20 above set forth includes a flat locking-member which is pivotally secured to the body of the receptacle and frictionally held in any rotated position by a spring-member. The cover is provided with a circular opening in 25 which the locking-member is closely received in the closed position of the cover to thereby hold the cover in such position. The cover is provided with a slot extended from the bottom edge to the opening therein which, 30 when the flat locking-member is turned into one position permits the cover to be moved into closed position and the locking-member to thereby enter the opening. The locking-member is thereupon rotated in said opening 35 to such a position that its edges engage the walls of the opening and removal of the cover is thereby prevented.

Figure 1 is a front view of a receptacle embodying my invention.

40 Fig. 2 is a detail of the cover and body of the receptacle with the cover in partially closed position and with the locking-member rotated into a position to enter the opening in the cover.

45 Fig. 3 is a sectional detail along lines 3—3 of Fig. 2.

Fig. 4 is a detail of the cover in closed position on the body of the receptacle and with the locking-member received in the opening 50 in the cover and with the locking-member rotated into locking position.

Fig. 5 is a sectional detail along lines 5—5 of Fig. 4.

55 Fig. 6 is a plan view of the friction washer for the locking-member.

As here shown the receptacle to which my invention is applied comprises the body-portion 10 and the cover 11. The cover is formed with a down-turned edge-portion 12 adapted to fit closely over the body-portion 10 in the closed position of the cover.

The locking-member comprises a flat strip having a locking-portion 14 and the integral reduced or bearing-portion 15. An opening 16 is formed through the wall of the body-portion near the top thereof and within that portion covered by the down-turned edge-portion 12 of the cover in the closed position thereof and the reduced or bearing portion 15 of the locking-member is rotatable therein. Said bearing-portion 15 is of such a length as to extend beyond the inner face of the wall of the body-portion 10 and a spring-member comprising the concave spring-disk 17 having a slotted periphery thereby to provide a plurality of spring-fingers 17' is arranged thereover and secured thereto as by the upsetting of the end of the bearing-member. The tension-member is for the purpose of drawing the shoulder formed at the junction of the locking and bearing portions of the locking-member into firm frictional engagement with the body portion 10 thereby to frictionally retain said locking-member in any rotated position against any unintentional displacement therefrom, yet permitting it to be rotated, and also firmly to hold it in extended position from the body-portion. The large diameter of the friction-member with its bearing with the wall of the receptacle at its periphery materially assists in providing this result. It is obvious, however, that any suitable means to accomplish this result may be employed.

The down-turned edge-portion 12 of the cover is formed with a substantially circular opening 18 therethrough which, in the closed position of the cover, is adapted to be substantially concentric with the pivotal axis of the locking-member. Said opening 18 is of such a diameter that it closely conforms to the edges of the locking-portion of the flat locking-member, whereby, when said member is rotated to a horizontal position shown in Figs. 4 and 5, 105 or to a position inclined away from the vertical, the walls of the opening will engage the edges of the locking-member and further movement of the cover toward an open position will be prevented.

A slot 19 is formed in the down-turned cover-portion and extended from the lower edge thereof to said opening 18 therein, to permit the entrance of the locking-member into said opening to lock the receptacle. Said slot is of a width slightly exceeding the thickness of the flat locking-member whereby, when said member is arranged as in Fig. 2 with the flat member in a vertical plane, or in the plane of the closing movement of the cover, the down-turned edge will move over the locking-member and assume a position in which the locking-member is entirely disposed in the opening 18 therein, as shown by the dotted lines in Fig. 4. The locking portion of said locking-member in the closed condition of the receptacle is such that it extends beyond the receptacle a suitable distance to be grasped by the fingers.

With the cover in closed position the locking-member is adapted to be rotated from the vertical position into a position inclined from the vertical, as in Fig. 4, in which position the edges of the locking-member engage the walls of the opening and prevent removal of the cover. The locking-member is frictionally retained in any adjusted position by the spring-member and consequently will hold the cover closed until it is rotated into adjustment with the slot 19, whereupon the cover may be moved away from the body of the receptacle.

It is to be noted that, by the provision of the substantially circular locking opening in the cover-portion and the locking-member which is closely received therein,

the cover is held firmly in closed position against movement in either direction.

I claim—

A receptacle having a body-portion and a cover having a side-wall depending down over a side-wall of the body-portion, the cover side-wall having a circular lock-member receiving an aperture therethrough and a slot having a width less than the diameter of said aperture extended from the lower edge of the side-wall to said aperture arranged to admit a lock-member within said aperture, the side-wall of said body-portion having a smaller aperture aligned with the aperture in said cover, and a lock-member for said cover and body-portion comprising a flat strip having a width approximately equal to the diameter of the circular aperture and a thickness less than the width of said slot and extended beyond the side-wall of the cover, said strip having a reduced portion rotatably received in the aperture in the side wall of the body-portion and extended inwardly beyond said side-wall, and a spring-plate received on said extended reduced portion arranged to press said strip against the side wall, said extended reduced portion formed with an enlarged inner end-portion arranged to retain said spring-plate in place.

In testimony whereof, I have signed my name to this specification, in the presence of two subscribing witnesses.

GEORGE A. BURNHAM.
